ABSTRACT

A grip which allows the skier to hold said grip directly so that he may release the latter in the case of an emergency, for instance if he drops off a ski lift and the ski-stick is entangled with the latter. To this end, the grip carries a tassel the outer ends of which are secured respectively to the upper and lower ends of the actual grip. Thus the skier passes four fingers through the gap left between the tassel and the grip so as to grasp the grip with said fingers, his thumb remaining outside said grip.

GRIP FOR SKI-STICKS AND THE LIKE

Ski-sticks are provided at their upper end with a grip carrying a looped tassel. In the tassel-carrying grips produced hitherto, the tassel has its two strands applied together and secured together to the upper end of the grip and the skier's hand extends entirely through the loop constituted by such a tassel which hangs thus off the skier's wrist.

Such prior tassel-carrying grips are objectionable since the skier if he falls off a ski-lift may be caught by the pole of the latter and consequently be seriously wounded.

The present invention has for its object an improved tassel-carrying grip which removes this drawback. Said grip is accordingly engaged at its lower end by one strand of the tassel the other strand of which is secured as usual to the upper end of the grip. Thus the tassel forms only one half of the loop which is to be engaged by the skier's hand so that the latter may hold the grip fast.

This arrangement cuts off the risk of the skier being caught by the ski-lift if he drops off the latter his hand releasing naturally the tassel as soon as a traction is exerted on the ski-stick.

When skiing downwards or during a slalom, the skier engaging the loop formed by my improved tassel with the grip can control his movements more accurately since his sticks are always securely held in his hands and the risk of being caught by a gate is small.

The first mentioned strand of the tassel may be secured to the lower end of the handle but in a preferred embodiment, said strand extending upwardly within a recess in the grip which recess is also engaged by the actual stick; in this case the ends of the two tassel strands can be secured by the same means to the upper end of the grip.

I have described hereinafter by way of example and by no means in a limiting sense an embodiment of my improved tassel-carrying grip, reference being made to the accompanying drawings wherein:

FIG. 1 is a sectional longitudinal view of the grip.

FIGS. 2 and 3 illustrate the manner of holding a ski-stick provided with the grip shown in FIG. 1.

Turning to FIG. 1, the grip is provided with a blind axial bore 2 in which the ski-stick 3 is to be fitted (see FIGS. 2 and 3).

The tassel 4 is of the type wherein the length of the loop is adjusted by a buckle 5. One of the strands 4a of the loop engages through its free end a transverse slot 6 extending across one side of the upper end of the grip 1 and it is secured to the latter by means of a screw 7. The other strand 4b of the loop extends upwardly inside the recess 2, so that its end abuts against the upper closed end of said recess to which it is secured by the same screw 7 as the first-mentioned strand.

When using such a grip and tassel the skier inserts his hand 15 within the half-loop formed by the tassel 4 but only over four fingers, leaving the thumb outside as an abutment for the tassel (FIGS. 2 and 3), the skier's hand grasps thus energetically the grip, but releases immediately and naturally the tassel whenever a traction is exerted on the ski-stick 3.

Obviously, my invention is by no means limited to the embodiment described and illustrated and it covers in contradistinction all the modifications thereof falling within the scope of the accompanying claims.

What I claim is:

- 25 1. A grip system for ski-sticks comprising a grip body adapted to be rigidly secured to the upper end of a stick and a tassel including two strands the ends of which engage respectively the upper and lower ends of the grip body to form with the latter a gap adapted to be engaged by the skier's hand 30 grasping the grip, the grip having a downwardly open blind axial bore adapted to be engaged by the upper end of the stick and by one strand of the tassel, the end of which is secured to the upper end of the blind bore.

2. A grip system as claimed in claim 1, and means extending 35 through the upper closed end of the bore to secure to the opposite sides of said closed end the ends of the corresponding tassel strands.
